UNITED STATES PATENT OFFICE.

EDWARD P. MCKINNEY, OF BINGHAMTON, NEW YORK.

STAND FOR PRESSING-IRONS.

1,164,108.

Specification of Letters Patent. Patented Dec. 14, 1915.

Application filed January 11, 1915. Serial No. 1,574.

To all whom it may concern:

Be it known that I, EDWARD P. MCKINNEY, a citizen of the United States, and a resident of Binghamton, in the State of New York, have invented certain new and useful Improvements in Stands for Pressing-Irons, of which the following is a specification.

My invention relates to stands for Pressing-irons and the like, and has for one of its 10 principal objects to provide a stand so constructed that there is no danger from fire caused by a superheated iron.

In this invention ample circulation of air is provided about the iron and the stand, 15 which is constructed so as to be not easily upset, and in such a manner that the iron cannot easily slip off.

The invention consists in the novel construction, arrangement and combination of 20 various devices, elements, and parts, as illustrated in the accompanying drawings, and hereinafter more particularly described.

In the said drawings, Figure 1 is a side elevation of my improved stand; Fig. 2 is a 25 longitudinal vertical section taken on the line 2—2 of Fig. 4, and looking in the direction of the arrows; Fig. 3 is an end view, looking from the rear; and Fig. 4 is a plan view.

In carrying my invention into effect in the embodiment thereof which I have selected 30 for illustration in the accompanying drawings and description in this specification, I provide a base-member of preferably an approximately semi-cylindrical shape, constructed of rolled steel or some other suitable material, designated 11, one end of this member being, however, of slightly smaller diameter than the other end, as may be readily seen from the drawings. This member 11 is provided with outwardly turned flanges 12, by means of which it is adapted to rest firmly in a horizontal position. I also provide a member 13 upon which the iron is 35 adapted to rest. This member is formed from a piece of suitable material, approximately of the same shape as the base of a flatiron. The metal forming this member is so bent as to form a longitudinal groove or depression having an approximately rectangular cross-section and a portion on each side thereof upon which the side edges of the iron are adapted to rest. Each of these side portions is formed with a downward inclination toward said longitudinal depression, in order that merely the edge of the

iron resting thereon may come in contact therewith and the amount of heat communicated to the stand from the iron be thus reduced to a minimum. The edges of the 60 metal are also bent, forming upwardly extending flanges 15 adapted to prevent the iron from slipping off the stand. This member 13 is secured to the member 11 in the manner now to be described.

I provide members 16, (preferably two) 65 which may be stamped out of sheet metal, of the form shown in the drawings, that is, in the shape of a shallow cup. Each of these members 16 is filled with fire-proof non-heat-conducting material, such as asbestos fiber, designated 17. A rivet 18 passes vertically through the bottom of each member 16, and through the material contained therein. The lower end of the rivet is secured to 70 the top of the member 11, while the upper end is secured in the bottom of the groove 14 of the member 13.

It will be observed that when the member 11 is in its normal or horizontal position, one 80 end is somewhat lower than the other, and that as the members 16 are approximately of the same size, one end of the member 13 will also be lower than the other. By reference to the drawings it will be seen that 85 this is the end adapted to receive the front of the iron.

The principal advantages of my invention are as follows: On account of the forward inclination mentioned in the preceding paragraph, and on account of the fact that the lower end of the member 13 is partially provided with a flange, it is impossible for the iron to slip off, although it is very easy to place the iron on the stand, by 90 sliding it forward from the higher rear end, which has no flange. As only the edges of the iron rest on the member 13, the conduction of heat from one to the other is decreased, while on account of the shape of 95 this member 13, which has a large surface on both sides exposed to the air, it is possible for most of this heat to radiate. No heat can be communicated to the member 11 except through the rivets 18 and a small 100 portion of the sides of the cups 16, and as this area is very small, it is hardly possible for much heat to reach the member 11. The member 11 has practically its entire surface 105 on both sides exposed to the air, and so most of the heat communicated to it is quickly radiated, while from the relatively small 110

portion which rests on the table, the amount of heat radiated would be negligible. It will thus be seen that when my iron-stand is used, there is practically no danger of fire from a superheated iron or even of the scorching of any material upon which the stand may be placed.

Having thus described my invention what I claim as new and desire to secure by Letters Patent is as follows:

1. A stand for pressing irons and the like, comprising a base member and an upper member adapted to receive and hold a pressing iron, and means adapted to secure said members together, said upper member being inclined upwardly and outwardly from the center, whereby it is adapted to receive the edges of a pressing iron placed thereon.

2. A stand for pressing irons and the like, comprising a base member and an upper member adapted to receive and hold a pressing iron, and means adapted to secure said members together, said upper member being provided with a depression extending longitudinally and approximately along its middle line.

3. A stand for pressing irons and the like, comprising a base member, an upper member adapted to receive and hold a pressing iron, means adapted to secure said members together, said upper member being pro-

vided with a depression extending longitudinally and approximately along its middle line and the portions of said upper member on each side of said depression being inclined upwardly and outwardly.

4. A stand for pressing irons and the like, comprising a base member, an upper member adapted to receive and hold a pressing iron, heat insulating means between said base member and said upper member, and means adapted to secure said members together, said heat insulating means comprising a cup shaped member containing a disk of asbestos or the like.

5. A stand for pressing irons and the like, comprising a base member of arched form and an upper member adapted to receive and hold a pressing iron, and means adapted to secure said members together, said upper member being provided with a depression extending longitudinally and approximately along its middle line.

In witness whereof I have hereunto signed my name this 7th day of January 1915, in the presence of two subscribing witnesses.

EDWARD P. McKINNEY.
